UNITED STATES PATENT OFFICE.

GEORGE H. SHEARS, OF BENTON HARBOR, MICHIGAN, ASSIGNOR TO BAKER-VAWTER COMPANY, OF BENTON HARBOR, MICHIGAN, A CORPORATION OF MICHIGAN.

DESIGN FOR A COVER FOR LOOSE LEAF BINDERS OR THE LIKE.

Application filed April 15, 1925. Serial No. 13,134. Term of patent 14 years.

To all whom it may concern:

Be it known that I, GEORGE H. SHEARS, a citizen of the United States, residing at Benton Harbor, in the county of Berrien and State of Michigan, have invented a new, original, and ornamental Design for Covers for Loose-Leaf Binders or the like, of which the following is a specification, reference being had to the accompanying drawing, forming part thereof.

The single figure of the drawing is a plan view of a cover for a loose leaf binder, or the like, showing my new design.

I claim:

The ornamental design for a cover for loose leaf binders or the like, as shown.

GEORGE H. SHEARS.
